D8-302.

OR D19.272

EX

UNITED STATES PATENT OFFICE.

JOHN E. HARBSTER, OF READING, PENNSYLVANIA, ASSIGNOR TO THE READING HARDWARE COMPANY, OF SAME PLACE.

DESIGN FOR THE ORNAMENTATION OF HARDWARE.

SPECIFICATION forming part of Design No. 19,272, dated August 20, 1889.

Application filed July 3, 1889. Serial No. 316,444. Term of patent 7 years.

To all whom it may concern:

Be it known that I, JOHN E. HARBSTER, a citizen of the United States, residing at Reading, in the county of Berks and State of Pennsylvania, have invented and produced a new and original Design for the Ornamentation of Hardware; and I do declare the following to be a full, clear, and exact description of the same, reference being had to the accompanying engraving, forming a part thereof.

This design is intended for the ornamentation of various articles of hardware, such as door-handles, butts, knobs, escutcheons and bells, hinges, furniture-hardware, &c.

The illustration filed herewith shows my design applied to a store-door handle, and clearly illustrates its essential features.

The main element of the design consists in the figure formed upon the background A, which figure represents bundles of threads crossing each other at right angles and tied together at their intersecting points by single diagonal threads a, which latter cross each other in the center of the blocks formed by the raised bundles of threads. The border or beading B is raised above the design.

The illustration also shows a panel C between the raised border B and an outside border or beading D upon the same level as B, upon which panel appears the representation of a chain c, raised above the background of the panel and forming a frame surrounding the main panel A.

I intend to use the chain-panel just described wherever the size and shape of the article will permit it to be placed advantageously; but the essential feature of my design is the recessed panel A, representing knotted bundles of threads, as described, and this figure, with the beading and chain-panel, may be variously adapted to all suitable articles of hardware, substantially as herein set forth.

What I claim is—

The design for the surface ornamentation of a door-handle or other article of hardware, as herein described and shown.

In testimony whereof I affix my signature in presence of two witnesses.

JOHN E. HARBSTER.

Witnesses:

C. E. SCHROEDER,
FRANK KISSINGER.
